UNITED STATES PATENT OFFICE.

ARVID H. NERO, OF NEW BRITAIN, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

1,420,569.

Specification of Letters Patent. Patented June 20, 1922.

Application filed November 10, 1917. Serial No. 201,235.

To all whom it may concern:

Be it known that I, ARVID H. NERO, a citizen of the United States of America, and residing at New Britain, in the county of 5 Hartford and State of Connecticut, have invented a certain new and useful Improvement in Electric Switches, of which the following is a specification.

My invention relates to electric switches 10 and particularly to rotary snap switches, the object of my invention being to provide a simple and efficient switch construction which may be economically manufactured and readily installed.

15 In the accompanying drawings,

Fig. 1 is a vertical section through a switch in which my invention is embodied in one form;

Fig. 2 is an inverted plan thereof;

20 Fig. 3 is a vertical section thereof at right angles to Fig. 1;

Fig. 4 is a perspective of the switch bar and its carrier sleeve;

25 Fig. 5 is a perspective of one of the combined line and switch terminals shown in inverted position; and

Fig. 6 is a dropped perspective of the switch spindle and parts mounted thereon.

The present switch is of the surface type 30 and comprises an insulating body 10 of inverted cup shape adapted to rest upon any suitable support 11, to which it is secured by screws 12 and 13 passing through the top of the body 10 and down through the switch 35 chamber 14 enclosed by the side wall 15 of the body. Within the switch chamber 14 and on opposite sides thereof are mounted combined wire terminal and switch plates 16 and 17 secured to the top of the insulating 40 casing by means of screws 18. Each wire terminal comprises a standard with offset flange 19 carrying a binding screw 20 for one of the leading-in wires which enter the switch chamber through grooves 21 in the 45 lower edge of the flange 15 of the casing. The offset base flange 22 of each terminal receives the securing screws 18 and is extended inward to form an arcuate switch terminal provided at one end with an upwardly 50 inclined lug 23. When the switch is installed slightly below the level of surface 11, the wires may be led in through holes 44, 45, piercing the side wall of the casing. These 55 holes may be used for egress of the wires

when a running connection for the switch 55 is desired.

On the inner face of the top of the casing and surrounding a central, well 24 are formed two arcuate ratchet teeth 25. These ratchet teeth 25 have substantially the same 60 arcuate extent as the base flanges 22 of the terminals and alternate with the latter. A bump 26 at the low end of each tooth serves to support the rise 23 at the adjacent end of the switch terminal flange, while the rise 65 at the opposite end of the tooth lies above the adjacent end of the switch terminal and affords a quick "make" of the connection between the switch terminals by the switch 70 bar 27, just as the rise 23 at the end of the switch terminal insures a quick "break" of the circuit when the switch bar drops therefrom to the depressed area of the arcuate tooth 24.

The switch bar 27 is mounted on switch 75 spindle 28 which passes upward through the top wall of the insulating casing and is engaged above the latter by the thumb piece 29. The latter is preferably of porcelain and is pierced to permit the body of the 80 spindle to pass therethrough but is provided with a non-circular well 30 in its outer end to receive the wing shaped head 31 which affords an engagement between the thumb piece and the spindle. The inner end portion of the spindle is non-circular in cross-section and has adjacent its extremity a slot 32 to receive the split retaining washer 33 which holds the mechanism in place thereon. An operating dog in the form of a four 85 armed washer 34 is slipped over the non-circular portion of the spindle and is rotated thereby. Juxtaposed thereto on the spindle is a ratchet disc 35 having upstanding lugs 36 which engage in notches 37 in the sides 90 of the switch bar 27 so as to cause the latter to rotate therewith. These lugs 36 are beveled at 38 on one face to permit the switch bar 27 to lag behind the ratchet 35 when the latter is rotated by the dog 34. This 95 permits the spring 39, coiled upon the carrier sleeve 40, to be gradually compressed as the switch bar rises over the inclines 23 or 25 and thus insures an easier action for the switch than would be the case were the 100 lugs 36 provided with parallel faces. The spring 39 is confined between the end flange 41 of the sleeve and the face of the switch

bar. A supplemental spring 42 may be interposed between the ratchet plate and the opposite face of the switch bar to insure the continued engagement of the ratchet plate 5 and dog when the switch bar rises over the inclines 23 and 25, at which time of course the pressure of the main spring 39 upon the switch bar is not transmitted to the ratchet plate. The opposite end of the 10 sleeve 40 is spread above the upper face of the ratchet plate, thus forming an assembly unit comprising the sleeve 40, spring 39, notch bar 27, spring 42, and ratchet plate 35. A bearing washer 43 may be interposed 15 between the inner end of the sleeve 40 and the retaining washer 33 to insure the free action of the switch.

The operation of the switch is readily understood. When the spindle 28 is rotated 20 by the thumb piece 29, the dog 34 engages the ratchet 35 and rotates the latter. Inasmuch as the lugs 35 of the latter engage the switch bar the movement is imparted to the latter. As the switch bar moves with 25 the spindle it encounters the rises 23 and 25 which oppose its rotation. The switch bar moves lengthwise of the spindle under the continued pressure of the ratchet, rising partially through its bearing on the inclines 23, 25 and partially through the camming action of the inclined faces 38 of the lugs 36. During this action it lags behind the ratchet plate but is finally rotated over 30 the tops of the inclines and is then moved 35 with the spindle until it clears the rises whereupon it is pressed downward by the main switch spring 39 upon the contact plates or the interposed arcuate teeth, thus "making" or "breaking" the switch with a 40 snap action. Inasmuch as the switch bar 27 rides down the inclines 38 of the lugs 36 of the ratchet 35 under the influence of the coil spring 39, a positive forward throw is imparted to the switch bar which serves to 45 increase the speed and length of the break between the switch bar and the contacts 22. The added length of break thus secured increases the current capacity which the switch can safely control.

50 Various modifications in detail will readily occur to those skilled in the art which do not depart from my invention and the latter is not limited to the details shown and described.

55 I claim:—

1. In an electric switch, an insulating body having a hill and valley course, switch terminals lying in alternate valleys of said course, a rotary switch bar traveling said course, a rotary cam having inclines engaging the switch bar, the inclines of the said cam being of less pitch than the declines of the course, means to actuate said cam to lift the switch bar over the hills of the course, the 60 switch bar lagging behind the cam during its

rise over a hill portion of the course, and a spring freely engaging the switch bar to force the latter down the inclines of the cam after it passes the crest of the hill and thus to cause a forward rotation of the switch 70 bar into the succeeding valley of the course.

2. In the construction specified in claim 1, a ratchet driver for actuating the operating cam.

3. In a construction such as specified in 75 claim 1, offset flanges at the ends of the switch terminals, said flanges serving as detents to hold the switch bar against rotation until lifted thereover by the cam.

4. In an electric switch, a switch spindle 80 having a ratchet dog rotating therewith, a cooperating ratchet plate with offset lugs and a switch bar freely engaged by said lugs to permit the relative displacement of said switch bar lengthwise of the spindle while 85 engaged by said lugs.

5. In an electric switch an assembly unit comprising a flanged sleeve adapted to fit freely over a switch spindle, a switch bar rotatable on said sleeve, a switch spring 90 coiled on said sleeve and confined between one end flange thereof and the switch bar, a ratchet plate bearing against the opposite end flange of said sleeve and lugs thereon freely engaging said switch bar to rotate the 95 latter while at the same time permit its relative longitudinal displacement on said sleeve.

6. In an electric switch an assembly unit comprising a flanged sleeve adapted to fit freely over a switch spindle, a switch bar 100 rotatable on said sleeve, a switch spring coiled on said sleeve and confined between one end flange thereof and the switch bar, a ratchet plate bearing against the opposite end flange of said sleeve and lugs thereon 10 freely engaging said switch bar to rotate the latter while at the same time permit its relative longitudinal displacement on said sleeve, together with an auxiliary spring 110 interposed between said switch bar and ratchet plate.

7. A rotary switch of the hill and valley type comprising a rotary switch bar following the hill and valley course, a spring freely engaging said switch bar to press it toward 115 said course, and a cam device for assisting the rise of the switch bar over the hills of its course against the action of the switch spring, the pitch of the cam being less than the pitch of the declines of the course, said 120 switch bar lagging behind the cam during the actuating movement of the latter, and riding down the cam with a positive forward throw as it leaves the hill crest under the pressure of said switch spring.

8. An electric switch comprising rotary switch bar, alternating hill and valley conducting and non-conducting members on which it rests in successive positions, a spring 125 freely pressing the switch bar toward said 130

members, and an actuating member having inclines engaging said switch bar to lift it with lagging action over the successive hills and down which inclines the switch bar rides 5 as it moves from hill to valley position, the pitch of the inclines of the actuating member being less than that of the declines of the course.

9. In an electric switch, an insulating casing with inverted cup shape, a spindle piercing the top thereof, arcuate ratchet teeth on the inner face of the insulating casing and concentric with said spindle, switch terminals mounted within said casing and alter-

nating with said ratchet teeth, a switch bar 15 spring-supported on said spindle within the casing, a thumb piece engaging the spindle outside the casing and a ratchet-operated cam for the spindle and engaging the switch bar to lift the latter over the rises of the 20 ratchet teeth of the casing and rotate the bar, under the pressure of its supporting spring, to cause said bar to ride upon co-operating terminals or ratchet teeth alternately, substantially as described. 25

In testimony whereof I have signed my name to this specification.

ARVID H. NERO.
